REFLECTING SIGN

Richard P. Benoit, Worcester, Mass., assignor to
 McKenzie Engraving Co., Boston, Mass., a corporation of Massachusetts

Application December 9, 1933, Serial No. 701,688

10 Claims. (Cl. 40—135)

This invention relates to reflecting signs and has for its object the production of a simple and inexpensive article of this character adapted to be secured to the glass of a window or the like, and provided with letters or other characters which will stand out as if illuminated when the rays of the sun, a headlight, or other means are projected thereon.

This object is attained by the arrangement and combination of elements illustrated in the accompanying drawing.

For the purpose of illustrating the invention, one preferred form thereof is illustrated in the drawing, this form having been found to give satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claims.

In the drawing

Figure 1 represents a sign embodying the principles of the present invention.

Figure 2 represents a vertical transverse section of same drawn to an enlarged scale with the thickness of the materials used greatly exaggerated.

Figure 3 represents a front elevation of a portion of said sign and showing a single letter having perforations therein behind which is disposed an indented metal foil having a reflecting surface.

Figure 4 represents a longitudinal vertical section of one end of said sign and showing a supporting gummed tab applied thereto, and

Figure 5 represents a front elevation of a portion of the sign and showing a single perforation in a letter with a backing of indented metal foil.

Similar characters indicate like parts throughout the several figures of the drawing.

In the drawing, 10 and 11 are two parallel sheets of cardboard preferably joined together at the upper end by a fold 12 and gummed together at their lower ends, as indicated at 13.

Interposed between these parallel sheets 10 and 11 is a metal sheet 14 having a reflecting front face.

The front face of the sheet 10 is provided with a panel 15 of one color surrounded by a border 16 of a different color.

On the panel 15 a plurality of designating characters 17 are printed, these characters 17 having a color different from that of the panel 15.

The designating characters 17 may be letters, figures, or other configurations, as desired.

These designating characters 17 may be combined in any suitable manner to convey any desired information.

As shown in the drawing the characters indicate the State in which a car bearing the sign is registered.

Primarily the reflecting sign is indicated for use as a greeting sign, as for instance, "Merry Christmas" or "Happy New Year".

In a sign conveying a greeting "Merry Christmas" the panel 15 is preferably green and border 16 and letters 17 are in red.

Interposed between and secured to the opposite ends of the sign are gummed tabs 19, portions of which project beyond the sign and are adapted to be gummed to the back window of a motor car, or such signs may be secured in a similar manner to the rear face of a window of a house.

When thus secured to the back window of a motor car or a house window the greeting on the sign is clearly exposed to view in daylight.

When the designating characters 17 have been printed upon the front sheet 10 a plurality of openings 20 are formed in the sheet 10 exposing to view the metal sheet 14.

These openings 20 conform to the designating characters 17 and when the rays of a headlight are projected upon the sheet 10 the light therefrom will be reflected from the exposed face of the sheet 14 and make the designating characters 17 stand out brilliantly.

While a certain effect may be thus secured from the reflecting face of the sheet 14 through the openings 20, a much more brilliant effect may be secured by forming in said sheet 14 a plurality of depressions 21 having inclined sides 22.

Preferably each depression 21 registers with 40 and is centered in each opening 20.

The openings 20 may be disposed in the sheet 10 in the form of designating characters without the printing of such characters 17 on the sheet 10 but preferably the colored characters are 45 printed on the sheet and then the openings 20 formed within the boundaries thereof, as indicated in the drawing.

By this means the reflecting surfaces of the sheet 14 and the depressions 21 will make the 50 colored characters stand out more clearly.

In the daytime when the rays of the sun are projected upon the sign the characters 17 will stand out with great brilliancy owing to the rays of the sun being reflected through the openings 55.

20, these rays being deflected in different directions owing to the inclined sides 22 of the depressions 21.

In Fig. 2 of the drawing the sheet 14 is shown 5 greatly exaggerated in thickness but in actual practice this sheet will be of thin material and when the depressions 21 are formed therein portions of the material will be pressed into the face of the rear sheet 11.

10 When the signs have been made with the greeting "Merry Christmas" thereon and applied to the rear window of a motor car they will present a most attractive appearance and be very brilliant in daylight under the rays of the 15 sun and equally as brilliant at night when the rays of the headlights of the following car are projected thereon.

The signs are inexpensive to manufacture and 20 very attractive in appearance, and provide a very simple means of presenting the season's greetings to others.

It is believed that the operation and many advantages of the invention will be understood without further description.

25 Having thus described my invention, I claim

1. A sign having a plain panel with its outer 30 face provided with a plurality of characters of a different color, each character having within its boundaries openings therein, and a sheet of reflecting material at the rear of said panel having a depression therein centrally positioned behind each opening.

2. A sign having a plain panel having formed 35 on its outer face a plurality of characters of distinguishing color, each character having within its boundaries openings therein extending through said panel, and a sheet of reflecting material at the rear of said panel and exposed to view through said openings, said material having 40 centrally disposed behind each opening a square depression with flat inclined sides.

3. A sign having a plain panel provided with 45 a plurality of openings extending through said panel disposed in groups, each group forming a designating character and having a sheet of reflecting material at the rear of said panel and exposed to view through said openings, said material having a plurality of similarly shaped depressions of which one is positioned in the center 50 of and opposite each opening.

4. A sign consisting of a plain panel provided with a plurality of openings extending through

said panel disposed in groups, each group forming a designating character and a sheet of reflecting material at the rear of said openings, said reflecting material having centrally disposed opposite each opening a depression with a plurality of facets.

5. A sign consisting of two parallel panels, of which the front panel has a plurality of openings extending therethrough in groups, each group forming a designating character, and a thin 10 metal sheet disposed between said panels and having a plurality of similar depressions, one opposite each opening and within the boundaries thereof, each depression having a plurality of flat inclined facets facing in different directions. 15

6. A sign consisting of two parallel panels, of which the front panel has a plurality of openings extending therethrough in groups, each group forming a designating character, and a thin 20 metal sheet disposed between said sheets and having indentations with inclined sides, one of said indentations being opposite each opening.

7. A sign provided on its front face with a plurality of characters, each character having a plurality of openings therein, and a sheet of reflecting material having opposite the center of each opening a square flat-bottomed depression with flat inclined sides. 25

8. A sign consisting of a folded member having 30 a reflecting metal sheet interposed between the front and rear sheets thereof, the rear sheet being imperforate and said front sheet having a plurality of openings therein forming designating characters and said metal sheet having a 35 plurality of indentations therein, one registering with each opening.

9. A sign provided with a front panel having on its front face a plurality of characters each having within its borders a plurality of openings, 40 and a metal sheet behind said panel having a depressed reflecting surface behind the center of each opening and exposed to view therethrough.

10. A sign consisting of two parallel panels, the front panel having a plurality of openings disposed in groups therein and each group forming a designating character, a metal sheet between 45 said panels having a reflecting surface with an inclined flat sided depression exposed in each opening, and the rear panel being imperforate. 50
